(57) **CLAIM**

The ornamental design for a five-in one wireless charger, as shown and described.

DESCRIPTION

FIG. 1 is a front, bottom perspective view of a first embodiment of a five-in one wireless charger showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 1;

FIG. 11 is an enlarged view of detail "11" identified in FIG. 2;

FIG. 12 is an enlarged view of detail "12" identified in FIG. 2;

FIG. 13 is another perspective view thereof, shown in an alternative position;

FIG. 14 is a front, bottom perspective view of a second embodiment of a five-in one wireless charger showing my new design;

FIG. 15 is a rear, top perspective view thereof;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof;

FIG. 21 is a bottom plan view thereof;

FIG. 22 is an enlarged view of detail "22" identified in FIG. 14;

FIG. 23 is an enlarged view of detail "23" identified in FIG. 14;

FIG. 24 is an enlarged view of detail "24" identified in FIG. 15;

FIG. 25 is an enlarged view of detail "25" identified in FIG. 1; and,

FIG. 26 is another perspective view thereof, shown in an alternative position.

The dashed lines in the figures illustrate portions of the five-in one wireless charger that form no part of the claimed design. The dash dot dash lines in FIGS. 1, 2, 9, 10, 11, 12, 14, 15, 22, 23 and 24 are for the purpose of illustrating the enlarged view indicators and form no part of the claimed design.
